DISPOSABLE FORMULA CONTAINER FOR INFANT FEEDING

Raymond W. Barton, Donald E. Dailey, and Anton F. Ellers, all of Evansville, Ind., assignors to Mead Johnson & Company, a corporation of Indiana

Filed Oct. 25, 1961, Ser. No. 67,255

Term of patent 14 years

(Cl. D83—1)

FIGURE 1 is a side elevational view of a disposable formula container for infant feeding embodying our new design;

FIGURE 2 is a top plan view thereof; and

FIGURE 3 is a bottom plan view thereof.

This application is a continuation-in-part of our application, Serial No. D.64,646, filed April 6, 1961, and now abandoned.

We claim:

The ornamental design for a disposable formula container for infant feeding, as shown and described.
